UNITED STATES PATENT OFFICE.

HENRY S. AYLING, OF BLOOMINGTON, ILLINOIS, ASSIGNOR OF ONE-HALF
TO EDWARD AUTEN, OF PRINCEVILLE, ILLINOIS.

VALVULAR MECHANISM.

No. 801,058.

Specification of Letters Patent.

Patented Oct. 3, 1905.

Application filed October 17, 1904. Serial No. 228,714.

To all whom it may concern:

Be it known that I, HENRY S. AYLING, a citizen of the United States, and a resident of Bloomington, in the county of McLean and State of Illinois, have invented a new and Improved Valvular Mechanism, of which the following is a full, clear, and exact description.

The invention relates to a valvular mechanism particularly designed to control the steam movement in air-pumps employed in automatic air-brake systems.

The prime object of the invention is to provide a mechanism which will economize the steam consumption in pumps.

A duplex air-pump is now commonly employed in connection with fluid-pressure brake systems in which the compressor-pistons come to a comparatively prolonged rest at the end of each stroke and in which the valve controlling the inlet of the motive steam is held open until the return movement of the piston has begun. This is highly disadvantageous, inasmuch as with the inlet-valve thus open the steam in the compressor-cylinder in time equalizes with the boiler-pressure, and there results from this condition a much higher pressure in the pump-cylinder and a greater consumption of steam than is necessary.

My invention involves a certain peculiar arrangement of the valves and their actuating parts which causes the steam-inlet valve to close as the piston reaches the end of its stroke (thus preventing unnecessary consumption of steam) and the exhaust to be held covered during the time that the piston dwells at the end of its stroke.

The invention involves various other features of major or minor importance, all of which will be fully developed hereinafter.

The accompanying drawings illustrate the preferred embodiment of my invention applied to control the steam movement in a duplex steam-driven air-pump—such, for example, as is made by the New York Air Brake Company for use in connection with their fluid-pressure railway brake apparatus. Said air-pump has two cylinders, one a low-pressure cylinder discharging into the other or high-pressure cylinder, in which the air is further compressed.

In the drawings like characters of reference indicate like parts throughout the views.

In said drawings, Figure 1 is a vertical section essentially on the line 11 of Fig. 2, taken

through the steam-cylinders and showing the two reversing-valves and the live and exhaust steam passages. Fig. 2 is a vertical cross-section taken through the low-pressure cylinder on essentially the line 22 of Fig. 1, showing the live and exhaust steam passages, the low-pressure reversing-valve, and the low-pressure distributing and cut-off valves in cross-section. Fig. 3 is a horizontal section taken through the valvular mechanism on the plane of the live-steam passage, which is essentially that of the line 33 in Figs. 1 and 2. Fig. 4 is a horizontal section of the valvular mechanism, taken on the plane of the exhaust-steam passage, which is essentially that of the line 44 in Figs. 1 and 2. Fig. 5 is a detail view of one of the main or steam-distributing valves. Fig. 6 is a diagram illustrating the steam-cylinders, the pistons therein, with the live and exhaust steam passages, the reversing, distributing, and cut-off valves, and the various parts upon which the correct operation of my invention depends; and Fig. 7 is a detail view of one of the two-part bushings in which the main or steam-distributing valves, cut-off valves, and their differential actuating-pistons operate.

10 indicates the steam-cylinder connected with the high-pressure pump-cylinder, and 11 the steam-cylinder connected with the low-pressure pump-cylinder, which cylinders 10 and 11 for the purpose of illustration it may be assumed are identical with the steam-cylinders of the duplex air-pump forming a part of the New York Air Brake Company's automatic air-brake system, the high-pressure and low-pressure air-cylinders lying, respectively, above the steam-cylinders 10 and 11 and carrying compressor-pistons, respectively, in direct connection with the pistons of said cylinders. The lower head 12 of the steam-cylinders is bolted or otherwise suitably fastened to the cylinder-walls and carries the improved valvular mechanism in essentially the same position as in the commonly-known air-pump above referred to, and the piston-rods of both pistons are hollowed to receive the reversing-rods 14, by means of which the reversing-valves 15 are automatically actuated at the end of each stroke of the steam-pistons, as will be fully understood from the prior art.

16 indicates the steam supply and 17 indicates the exhaust pipe. The steam-pipe 16 communicates with a horizontal steam-passage 18, formed in the walls of the steam-

head and preferably passing through the same from one end to the other, the end opposite the pipe 16 being fitted with a plug 19, securely yet removably to close the same. 5 The exhaust-pipe 17 leads from an exhaust-chamber 20, formed in the steam-head 12 at a point above the live-steam chamber 18, the passage 20 also in the preferred form of the invention passing completely through the casting forming the steam-head 12 and being fitted at the end opposite the pipe 17 with a plug 21, similar in form and purpose to the plug 19. Formed in the steam-head at each side of the steam-chamber 18 and preferably 10 in the horizontal plane thereof are the cavities 22 for the main valves and their immediately-allied parts. In each cavity 22 a two-part bushing is arranged comprising a cup part 23 and a sleeve part 24, the latter having a reduced diameter at the point 25 for the purpose which will hereinafter fully appear. The steam-passage 18 communicates with the cavities 22 by means of ports 26, extending from opposite sides of the steam passage or 15 chamber, respectively, into the large diameters of the bushing-sections 24, so that when steam is turned into the chamber 18 it is constantly supplied to the interior of said bushing-sections through said ports 26.

20 The steam-head 12, which forms, as will be apparent, the casing for the valvular mechanism, is provided with two pairs of ports 27 and 28 and 27^a and 28^a, passing from the large diameter of each bushing-section 24 across the 25 casing to the oppositely-situated bushing-section 23. These ports as they enter the large diameters of the bushing-sections 24 are relatively close to each other and as they enter the bushing-sections 23 are spread apart, as shown 30 best in Fig. 3. The valve at the top of Fig. 3 immediately controls the steam-supply for the cylinder 11, and the valve at the bottom of Fig. 3 immediately controls the steam-supply for the cylinder 10. Leading from the lower end of 35 the low-pressure cylinder 11 into the cavity of the corresponding main or distributing valve (the top valve in Fig. 3) and communicating with said cavity in vertical line with the opening of the port 27^a is a steam-port 29, which 40 is intended to carry the steam to and from the lower side of the piston in the cylinder 11. Leading from the upper end of the cylinder 11 downward into the cavity of the corresponding main or distributing valve (the top valve in Fig. 3) is a port 30, which passes into 45 the cavity of said valve at a point immediately above the opening of the port 28^a into said cavity. This port 30 is designed to lead the steam to and from the upper side of the 50 piston in cylinder 10. Similar ports 29^a and 30^a pass from the cavity of the main valve corresponding to the cylinder 10, (the bottom valve in Fig. 3,) respectively, to the lower and upper ends of the cylinder 10, as shown 55 by the dotted lines in Fig. 2, and said ports 29^a and 30^a open into said valve-cavity, respectively, above the ports 28 and 27 in the same. Passing from both valve-cavities intermediate the ports 29 and 30 and 29^a and 30^a thereof are ports 31, both of which lead to 70 the exhaust-passage 20.

From the steam-passage 18 two passages 32 extend downward, and these are fitted with bushings 33, as shown. Operating in the said bushings are the before-mentioned reversing- 75 valves 15, with which the reversing-rods 14 are connected, as before explained. The said reversing-valves 15 are cornered off or grooved longitudinally to permit the steam to pass them. As shown best in Fig. 2, they are each 80 provided with a port 34. These ports, when the valves are in the downward position shown in Figs. 1 and 2, are intended to place in communication the exhausting-ports 35 and the feeding-ports 36 of each reversing-valve. 85 The said feeding-ports, as shown best in Fig. 3, pass, respectively, to the ends of the main-valve cavities 22 opposite the main valves to supply steam for operating said valve in one direction, as will be hereinafter fully explained, and the exhausting-ports 35 pass upward into the exhaust-cavity 20, as Fig. 2 illustrates. When the valves 15 rise from the position shown in Figs. 1 and 2, they cover 90 the exhausting-ports 35 and uncover the feeding-ports 36, and steam then passes down the sides of the reversing-valves and into the feeding-ports from below the reversing-valves. The main or distributing valves each comprises a cylindric body portion 37, provided 95 with a centrally-located indented port 38 and provided at its ends with a head 39 and 40, respectively, these heads being spaced upon the ends of the body of the valve by means of pillars 41. (See Fig. 5.) The said distributing-valves are fast on stems 42 and are located within the bushing-sections 23. The stems 42 pass into the cylindrical bushing-sections 24 and carry in the reduced part 25 a piston 43 and in the enlarged part of the said bushings 24 a piston 44. Intermediate said pistons 43 and 44 sliding cut-off valves 45 are mounted fast on the stem. 100

When the parts are in the position shown in Fig. 3, in which, as will hereinafter fully appear, the piston of the cylinder 10 is dwelling at the end of its downstroke and the piston of cylinder 11 is on its upward stroke, the steam or distributing valve of the cylinder 11 (the top valve in Fig. 3) occupies the following-described position with respect to the various ports communicating with the cavity 22 of said valve, to wit: The port 27^a, entering the cavity 22, is uncovered, opening into the space between the body 37 of the low-pressure valve and the head 40 thereof. The indented port 38 of the body 37 of the valve establishes communication between the exhaust-port 31 and the port 30, leading to the top of the low-pressure cylinder. The port 105 110 115 120 125 130

28^a, entering the bushing-section 23, is blanked by the body 37 of said valve. The port 28, entering the bushing-section 24 of said valve, is uncovered, and the port 27, entering the bushing-section 24 of said valve, is blanked by the cut-off valve 45. The distributing-valve of the cylinder 10 (the bottom valve in Fig. 3) occupies the following position with respect to the various ports, to wit: The port 28^a, entering the bushing-section 24, is blanked by the cut-off valve 45. The port 27^a, entering the bushing-section 24, is uncovered. The port 28, entering the bushing-section 23, is blanked by the body 37 of said valve. The port 27, entering the bushing 23, is uncovered, this port 27 communicating by the space between the body 37 and head 40 with the port 30^a, leading to the top of the cylinder 10, (see Fig. 6,) and the port 29^a, leading from the bottom of the cylinder 10, is in communication with the exhaust-port 31 by way of the indented port 38 of the body 37 of the valve.

Fig. 6 illustrates by diagram the position of all of the parts corresponding to that shown in Figs. 1, 2, and 3, and, referring to said diagram, it will be observed that the reversing-valve 15 of the piston in cylinder 11 is in position to place the ports 35 and 36 of said reversing-valve in communication, exhausting steam from the right-hand side of the piston 44 of the valve of cylinder 10. When this takes place, the action of the steam on and between the differential pistons 43 and 44 will cause the pistons and the connected distributing-valve 37 of cylinder 10 to move rightward into the position shown in the drawings. The diagram in Fig. 6 also assumes that the piston of cylinder 10 is at the end of its downward stroke, and consequently that the reversing-valve 15 of said high-pressure piston is in its downward position, so as to place the ports 35 and 36 of the valve of cylinder 11 into communication and cause the valve to move leftward, as the diagram shows, owing to the action of the steam on the differential pistons 43 and 44 of said valve. This being the position of the parts, it will be observed that steam will pass from the cavity 18 through the port 26 into the cavity between the pistons 43 and 44 of cylinder 10, and the port 27^a being uncovered by the cut-off valve 45 steam will be permitted to pass this port across to the valve of cylinder 11 and through the space between said valve and its head 40 upward into and through the port 29 to the under side of the piston or cylinder 11, moving said piston upward, as indicated by the arrow in the diagram. The said leftward movement of the valve 37 of cylinder 11 also results in throwing the exhaust-passage 31 and the port 30 into connection with each other, and steam will be exhausted from the top of the piston of cylinder 11 through the ports 30, 38, and 31 to the exhaust-cavity 20. This operation

will continue until the reversing-rod 14 on the piston of cylinder 11 moves upward the connected reversing-valve 15, such operation taking place when the piston of cylinder 11 reaches the end of its upward stroke. This 70 will cause the exhaust-passage 35 of the valve of cylinder 10 to be closed and opening the steam-admitting passage 36 of said valve, so that steam passes down through the passage 32 past the said reversing-valve and through 75 the passage 36 to the right-hand side of the piston 44 of the valve of cylinder 10, (the lower valve in Fig. 6.) The steam will then act on both sides of the piston 44, and the pressure thereon will be equalized, whereupon the 80 pressure on the piston 43 of said valve will act to shift the valve leftward, causing it to move the slide-valve 45 so as to blank the port 27^a and to uncover the port 28^a and also causing the body of the valve to move so as 85 to place the port 29^a in communication with the port 28 by reason of the space between the body 37 of the valve and the head 39 thereof. This said leftward movement of the valve of cylinder 10 will further move the port 38 90 so as to connect the port 30^a with the exhaust-passage 31 of the valve and to disconnect said port 30^a from the port 27. When these operations take place, the piston of cylinder 11 being at the end of its upward movement, the 95 port 27^a of the cylinder 11 will be covered and steam will be cut off from the under side of the piston of said cylinder, the cut-off valve 45 of the valve of cylinder 10 nevertheless holding the steam-pressure in the cylinder 11 below the piston thereof as to keep said piston in its upper position until a reversal of its movement is desired.

As the valve 37 of cylinder 10 moves leftward, as above explained, and places the port 29^a in communication with the port 28 steam passes from the valve-casing of cylinder 11 between the pistons 43 and 44 through the port 28, across the valve-cavity of cylinder 10, and into and through the port 29^a, starting 110 the piston of cylinder 10 upon its upward movement. The above-referred-to leftward movement of the valve 37 also causes the port 38 to be moved so as to connect the port 30^a with the exhaust-port 31, and this permits 115 exhausting the steam from the upper side of the piston, allowing said piston of cylinder 10 to move upward freely. This upward movement of the piston continues until the end of the stroke is reached, whereupon the reversing-valve connected to said piston 15 is raised, disconnecting the ports 35 and 36 of the valve of cylinder 11 and throwing the entering-port 36 into communication with the steam-passage 18 through the medium of the passage 32, before 120 described. Steam will then enter through the passage 36 of the valve of cylinder 11 and act against the outer side of the corresponding piston 44, equalizing the pressure on its piston and permitting the pressure on the piston 43 to 130

shift leftward the valve and its connections, said leftward movement of the valve and its connections resulting in connecting the port 29 with the exhaust-passage 31 of the valve of cylinder 11, permitting the exhaust of the steam which was previously held in the cylinder 11 under the piston thereof. Simultaneously the port 28^a will be placed in communication with the port 30 by reason of the space intervening between the valve-body 37 of cylinder 11 and the head 39 thereof, causing steam to pass from the valve-cavity of cylinder 11 between the pistons 43 and 44 thereof through the port 28^a, which is now uncovered by the cut-off valve 45 of cylinder 10 across the valve-cavity of cylinder 11 and into and through the port 30, exerting its pressure on top of the piston in cylinder 11 and causing the piston to begin its downward movement. At the same time that the valve 37 of cylinder 11 shifted rightward, as above explained, it caused the cut-off valve 45 of cylinder 11 to cover the port 28 and uncover the port 27, and the valve 37 of cylinder 10 being at the end of its leftward movement opposite that shown in the diagram in Fig. 6 it will be observed that the steam-feed on the under side of the piston of cylinder 10 through the port 29^a will be cut off from the cylinder 10, owing to the cut-off valve 45 of cylinder 11 covering the port 28. This will hold the piston of cylinder 11 in its upward position by the pressure of the steam already entered into the lower end of the cylinder; but it will prevent further supply of steam to the cylinder, and consequently it will prevent the unnecessary expenditure of this steam.

The piston of cylinder 11 was last referred to as moving downward, and when the end of its downward movement is reached it actuates the connected reversing-valve 15 again to assume the position indicated in the diagram, in which the ports 35 and 36 of the cylinder 11 are in communication, and steam 45 is then exhausted from the right-hand extremity of the valve-cavity of cylinder 10, permitting the action of the steam on the adjacent faces of the differential pistons 43 and 44 to return the valve of cylinder 10 and its connections to the rightward position indicated in the diagram. This will cut off the steam-supply to the top of the piston in cylinder 11 through the port 30 by reason of the cut-off valve 45 of cylinder 10 moving over the port 28^a, covering the same and preventing the further entry of steam, the steam already entered into the top of the cylinder 11 acting nevertheless to hold the piston in its lower position, as described. When the slide-valve 45 of cylinder 10 moves rightward to the position shown in Fig. 6 upon the piston of cylinder 11 reaching the end of its downward movement, it causes the port 28 to be disconnected from the port 29^a and said port

29^a to be connected with the exhaust-port 31 of cylinder 10 through the port 38 of the valve 37 of said cylinder. This allows the steam to be exhausted from the under side of the piston of cylinder 10. Simultaneously the port 27 will be placed in communication with the port 30^a through the space between the valve-body 37 of cylinder 10 and the head 40 thereof, and steam will be admitted on top of the piston in cylinder 10, moving said piston downward, it being understood that the valve 37 of cylinder 11 is yet in its rightward position. The downward movement of the piston of cylinder 10 continues until said piston reaches its bottom position, whereupon the reversing-valve 15 of cylinder 10 is moved downward to connect the steam exhausting and feeding passages 35 and 36 and causing the steam to be exhausted from the left-hand side of the piston 44 of the valve of cylinder 11. The steam then acting on the faces of the differential pistons 43 and 44 will serve to return the said valve to the leftward position, (shown in Fig. 6,) which results in the cut-off valve 45 of cylinder 11 blanking the port 27, so as to cut off the steam-supply on the upper side of the piston of cylinder 11, holding the steam on the upper side of the piston in order to retain it in this position. At the same time the valve 37 of cylinder 11 places the port 28^a and the port 29 in communication with each other through the space between the body 37 of the valve and the head 40 thereof and causes live steam to be admitted on the under side of the piston of cylinder 11, again starting the upward movement thereof, as is indicated in the diagram, and also allowing the steam on top of the piston to be exhausted through the ports 30, 38, and 31, as before explained. The result of this mechanism is therefore that I operate the steam-pistons, and consequently the air-compressing pistons connected thereto, as will be understood from the prior art, by an upward and downward movement followed by a prolonged dwell at the end of each movement, this action of the pistons being characteristic of the operation of the compound air-pump referred to above, and while holding the pistons at the end of their strokes I cut off the steam from the source of supply, so as to prevent unnecessary expenditure of steam, retaining, nevertheless, a certain quantity of steam in the steam-cylinders whereby to hold the pistons in the upper or lower position, as the case may be. Ordinarily when the pistons reach the end of their stroke the full steam-head is continued against the pistons and the cylinders are allowed to equalize with the boiler-pressure, this resulting in a great unnecessary expenditure of steam. I avoid this by cutting off the steam in the manner explained. In this novel function resides the essential part of my invention.

Having thus described my invention, I claim as new and desire to secure by Letters Patent—

1. In a valvular mechanism, the combination of a main or distributing valve, a cut-off valve coacting therewith, differential pistons having connection with the valves, and means for controlling the fluid-pressure exerted on said pistons whereby to operate the valves.

2. In a valvular mechanism, the combination of a main or distributing valve, a cut-off valve coacting therewith, differential pistons having connection with the valves, and means for controlling the fluid-pressure exerted on said pistons whereby to operate the valves, said means including periodically-operative reversing-valves.

3. In a valvular mechanism, the combination with a ported casing, of a main or distributing valve coacting therewith and comprising a body with an indented port therein and heads respectively spaced from and connected with the ends of the body part of the valve, a sliding cut-off valve coacting with the main valve, and means for operating said valves.

4. In a valvular mechanism, the combination with a ported casing, of a main or distributing valve coacting therewith and comprising a body with an indented port therein and heads respectively spaced from and connected with the ends of the body part of the valve, a sliding cut-off valve coacting with the main valve, and means for operating the valves, said means comprising differential pistons in connection with the valves and devices for controlling the application of fluid-pressure to said pistons.

5. In a valvular mechanism, the combination with a ported casing, of a main or distributing valve coacting therewith and comprising a body with an indented port therein and heads respectively spaced from and connected with the ends of the body part of the valve, a sliding cut-off valve coacting with the main valve, and means for operating the valves, said means comprising differential pistons in connection with the valves and devices including periodically-operative reversing-valves for controlling the application of fluid-pressure to said pistons.

6. In a duplex valvular mechanism, the combination with a ported casing of two distributing-valves, two cut-off valves respectively in connection with the distributing-valves, the cut-off valve of each distributing-valve controlling the ported communication to the opposite distributing-valve, and means for operating the valves.

7. In a duplex valvular mechanism, the combination with a ported casing, of two distributing-valves, two cut-off valves arranged to operate respectively in time with the distributing-valves, the cut-off valve of each distributing-valve controlling the ported com-

munication to the opposite distributing-valve, 65 and means for operating the valves.

8. In a duplex valvular mechanism, the combination with a ported casing, of two distributing-valves, two cut-off valves arranged to operate respectively in time with the distributing-valves, the cut-off valve of each distributing-valve controlling the ported communication to the opposite distributing-valve, and means for operating the valves through the medium of fluid-pressure. 70

9. In a duplex valvular mechanism, the combination with a ported casing, of two distributing-valves, two cut-off valves arranged to operate respectively in time with the distributing-valves, the cut-off valve of each distributing-valve controlling the ported communication to the opposite distributing-valve, and means for operating the valves through the medium of fluid-pressure and periodically-operative reversing-valves controlling said 85 means.

10. In a duplex valvular mechanism, the combination with a ported casing, of two distributing-valves, two cut-off valves arranged to operate respectively in time with the distributing-valves, the cut-off valve of each distributing-valve controlling the ported communication to the opposite distributing-valve, and means for operating the valves, said means comprising differential pistons in connection 90 with each set of valves and means for controlling the exertion of fluid-pressure on said pistons.

11. In a duplex valvular mechanism, the combination with a ported casing, of two distributing-valves, two cut-off valves arranged to operate respectively in time with the distributing-valves, the cut-off valve of each distributing-valve controlling the ported communication to the opposite distributing-valve, 100 and means for operating the valves, said means comprising differential pistons in connection with each set of valves and periodically-operative reversing-valves controlling the application of fluid-pressure to said pistons. 110

12. In a duplex valvular mechanism, the combination with a ported casing of two main or distributing valves, a sliding cut-off valve in connection with each main valve, the cut-off valves controlling the port communication 115 to the opposite distributing-valves, and means for operating the valves.

13. In a duplex valvular mechanism, the combination with a ported casing, of two main or distributing valves, a stem in connection 120 with each, a cut-off valve in connection with each stem, the cut-off valves controlling the port communication to the opposite distributing-valves, and means for operating the valves.

14. In a duplex valvular mechanism, the combination with a ported casing, of two main or distributing valves, a stem in connection 125 with each, a cut-off valve in connection with

- each stem, the cut-off valves controlling the port communication to the opposite distributing-valves, and means for operating the valves, such means comprising differential 5 pistons in connection with the valve-stems, and devices for controlling the application of fluid-pressure to said pistons.
15. In a duplex valvular mechanism, the combination with a ported casing, of two main 10 or distributing valves, a stem in connection with each, a cut-off valve in connection with each stem, the cut-off valves controlling the port communication to the opposite distributing-valves, and means for operating the 15 valves, such devices comprising differential pistons attached to said stems, and periodically-operative reversing-valves controlling the application of fluid-pressure to said pistons.
20. 16. In a duplex valvular mechanism, the combination with two motor-cylinders and a ported casing, of a distributing-valve for each motor-cylinder, a cut-off valve for each motor-cylinder, means for operating the valves, 25 the cut-off valves being respectively connected with the distributing-valves, and the cut-off valves controlling the port communication to the opposite distributing-valves.
17. In a duplex valvular mechanism, the 30 combination with two motor-cylinders and a ported casing, of a distributing-valve for each motor-cylinder, a cut-off valve for each motor-cylinder, and means for operating the valves by fluid-pressure.
35. 18. In a duplex valvular mechanism, the combination with two motor-cylinders and a ported casing, of a distributing-valve for each motor-cylinder, a cut-off valve for each motor-cylinder, and means for operating the 40 valves, said means for operating the valves comprising differential pistons in connection therewith and devices for controlling the application of fluid-pressure thereto.
45. 19. In a duplex valvular mechanism, the combination with two motor-cylinders, and a ported casing, of a distributing-valve for each motor-cylinder, a cut-off valve for each motor-cylinder, and means for operating the valves, said means for operating the valves 50 comprising differential pistons in connection with the valves, and periodically-operative reversing-valves controlling the admission of fluid-pressure to said differential pistons, and in connection respectively with the pistons of 55 said motor-cylinders.
60. 20. In a duplex valvular mechanism, the combination with two motor-cylinders and a ported casing, of a distributing-valve for each motor-cylinder, a cut-off valve for each motor-cylinder, means for operating the valves, cut-off valves controlling the port communication to the opposite distributing-valves, and the means for operating the valves, comprising reversing-valves respectively in connection 65 with the pistons of the motor-cylinders.
21. In a duplex valvular mechanism, the combination with two motor-cylinders and their pistons, and with a ported casing, of distributing-valves respectively for the motor-cylinders, cut-off valves respectively in connection with the distributing-valves, the cut-off valves controlling the port communication to the opposite distributing-valves, means for operating said valves by the application of fluid-pressure, and devices for controlling said 70 application of fluid-pressure.
22. In a duplex valvular mechanism, the combination with two motor-cylinders and their pistons, and with a ported casing, of distributing-valves respectively for the motor-cylinders, cut-off valves respectively in connection with the distributing-valves, the cut-off valves controlling the port communication to the opposite distributing-valves, means for operating said valves by the application of 75 fluid-pressure, and devices for controlling said application of fluid-pressure, said devices including reversing-valves respectively connected with the motor-pistons.
23. In a duplex valvular mechanism, the combination with two motor-cylinders and their pistons, and with a ported casing, of distributing-valves respectively for the motor-cylinders, cut-off valves respectively in connection with the distributing-valves, the cut-off valves controlling the port communication to the opposite distributing-valves, means for operating said valves by the application of 80 fluid-pressure, and devices for controlling said application of fluid-pressure, said devices including reversing-valves respectively connected with the motor-pistons.
24. In a duplex valvular mechanism the combination with two motor-cylinders and their pistons, and with a ported casing, of a distributing-valve for each motor-cylinder, a 85 stem in connection with each valve, a cut-off valve in connection with each stem, the cut-off valve controlling the port connection to the opposite distributing-valves, differential pistons connected with said stems, and reversing-valves respectively connected with the motor-pistons and controlling the application of 90 fluid-pressure to said differential pistons.
25. In a duplex valvular mechanism, the combination with two motor-cylinders and their pistons, and with a ported casing, of a distributing-valve for each motor-cylinder, a stem in connection with each valve, a cut-off valve in connection with each stem, the cut-off valve controlling the port connection to the opposite distributing-valves, differential 95 pistons connected with said stems, and reversing-valves respectively connected with the motor-pistons and controlling the application of fluid-pressure to said differential pistons, 100

the reversing-valves controlling the fluid-flow to the differential pistons of the distributing-valves of the motor-cylinder opposite to those with the pistons of which the reversing-valves have connection.

26. In a duplex valvular mechanism, the combination with two motor-cylinders and pistons therein, and with a ported casing, of two distributing-valves each comprising a valve-body with a port therein, and heads spaced from and connected to the ends of the valve-body, a stem in connection with each

distributing-valve, a cut-off valve in connection with each stem, the cut-off valves controlling the port communication to the opposite distributing-valves, and means for operating the valves. 15

In testimony whereof I have signed my name to this specification in the presence of two subscribing witnesses.

HENRY S. AYLING.
